Fig. 2

Fig. 3

Fig. 4

FIGURE 1 is an exploded perspective view of a combination guard and sprocket assembly for bicycles equipped with derailleur mechanism showing our new design.

FIGURE 2 is a front elevational view;

FIGURE 3 is a rear elevational view; and

FIGURE 4 is an end view as seen from the right-hand side of FIGURE 2.

The dominant features of our design reside in the portions shown in full lines.

We claim:

The ornamental design for a combination guard and sprocket assembly for bicycles equipped with derailleur mechanism, as shown and described.
